CLAIM

The ornamental design for pants, as shown and described.

DESCRIPTION

FIG. 1 is a front view of an ornamental design for pants showing my new design;

FIG. 2 is a rear view thereof;

FIG. 3 is another front view thereof;

FIG. 4 is a sectional view of FIG. 3 taken along line 4;

FIG. 5 is a sectional view of FIG. 3 taken along line 5; and,

FIG. 6 is a sectional view of FIG. 3 taken along line 6.

The broken lines shown throughout the views are for illustrative purposes only and form no part of the claimed design.
